United States Patent Office

Des. 196,326

Patented Sept. 17, 1963

196,326

CARRYING CASE FOR CIGARETTES OR THE LIKE

Robert E. Linderman, Orange, and Theodore Schiffman, Tustin, Calif.; said Linderman assignor to said Schiff-man

Filed Sept. 18, 1962, Ser. No. 71,755

Term of patent 14 years

(Cl. D58—11)

FIG. 1 is a front perspective view of a carrying case for cigarettes or the like showing our new design;

FIG. 2 is a right-side elevational view thereof;

FIG. 3 is a rear elevational view thereof; and

FIG. 4 is a bottom plan view thereof.

We claim:

The ornamental design for a carrying case for cigarettes or the like, as shown.
